UNITED STATES PATENT OFFICE.

WILLIAM GRIESSE, OF CHICAGO, ILLINOIS.

MALT-TURNING APPARATUS.

SPECIFICATION forming part of Letters Patent No. 394,965, dated December 25, 1888.

Application filed October 14, 1887. Serial No. 252,352. (No model.)

To all whom it may concern:

Be it known that I, WILLIAM GRIESSE, a subject of the Emperor of Germany, residing at Chicago, in the county of Cook and State 5 of Illinois, have invented a new and useful Improvement in Malt-Turning Apparatus, of which the following is a specification.

My invention relates, particularly, to an improvement in the turning or stirring apparatus, and is designed especially for use in a process of malting in which the barley after being steeped is introduced into long germinating-vats, in which it is maintained moist by the introduction through suitable conduits 10 of air properly regulated as to temperature and saturated with moisture by passing through perforated plates or partitions, over the surfaces of which water is caused to trickle. The germinating-malt requires turning or stirring at intervals, which in the process referred to is accomplished by means of stirring mechanism caused to travel automatically and slowly upon the lateral edges 15 of the vats first in one direction, and, when the stirring operation is again required, in the opposite direction, which movements back and forth intermittently are repeated as often as required until the germination reaches a stage at which the malt is ready for removal 20 to the drying-kilns.

The object of my invention is to provide an improved turning apparatus which shall operate to turn the malt more effectively than apparatus hitherto employed for the purpose. 25 To this end my invention consists in the general construction of my improved apparatus; and it further consists in details of construction and combinations of parts.

In the drawings, Figure 1 is a sectional elevation of a house provided with means for practicing the malting process hereinbefore referred to and illustrated in the present connection to produce a clear understanding of the operation of my improved apparatus, the 30 upper floor being provided with steep-tanks having hopper-bottoms, from which through the floor, by way of suitable chutes, the steeped grain is transferred to the germinating-vats on the floor below; Fig. 2, a horizontal section of the same, showing the germinating-vats side by side in plan view; Fig. 3, a view showing in sectional side elevation my

improved turning apparatus; Fig. 4, a broken sectional end view showing the reversible bucket detail of the device illustrated in Fig. 55 3, and Fig. 5 a cross-sectional view of a germinating-vat provided with my improved turning apparatus presented in end elevation.

A denotes the germinating-vats, which in the practice of the process referred to are 60 placed side by side in a suitable apartment, as shown in Fig. 1, leaving intervening spaces at which platforms are provided upon which to permit access by the workmen to the vats, and the bottoms of the vats are provided near 65 corresponding ends with hoppers *r*, through which the malt may be readily transferred when desired to an endless conveyer, *r'*, which elevates or carries it to the kiln-rooms.

Rotary shafts *A'*, Fig. 2, are supported to 70 extend transversely across the vats *A* near their ends, and carry pulleys *r*², which are connected by means of suitable endless belts with the driving-pulleys on the turning apparatus hereinafter described, and by the 75 rotation of one of the shafts *A'* the turning apparatus, one of which is supported on the upper lateral edges of each vat, is driven slowly in one direction to one end of the vat, and after a desired interval, by twisting the 80 driving-belt, is driven slowly in the opposite direction to the opposite end of the vat, the motion of the apparatus continually actuating the mechanism to turn the malt, as hereinafter described.

The connection of the driving-pulleys of the apparatus with those on the rotary driving-shafts is not illustrated in the present drawings, as it presents no features of novelty and is the same as that employed in similar 85 connections.

A description of my improved turning apparatus is as follows:

B is a rectangular frame, carrying near opposite ends transverse shafts *q* and *q'*, which 90 extend beyond opposite sides of the frame, where they are provided with wheels *p*, which rest upon tracks *p'* on the upper edges of the sides of a vat, *A*, and cog-wheels *o*, which engage with racks *o'* at the outer sides of the 95 tracks *p'* and also on the upper edge or edges of the sides of a vat. Between and above the shafts *q* and *q'* is supported a rotary shaft, *n*, carrying at one projecting end a belt-pul-

ley, C, and inside the frame a sprocket-wheel, m , connected by a chain, m^2 , with a similar wheel, m' , on a shaft, q' , as shown, or q , and a sprocket-wheel, l .

- 5 D and D', Fig. 5, are brackets rigidly secured to opposite sides of the frame B, to extend downward, and supporting near their lower ends at collars or hubs x , keyed or secured by set-screws within their bearings, a 70 transverse shaft, n' , carrying near one end a sprocket-wheel, l' , connected by means of a chain, l^2 , with the sprocket-wheel l on the shaft n , whereby the last-named shaft drives the shaft n' , upon which are fastened pulleys 75 k at desired intervals apart.

- 10 D² and D³ are arms rigidly secured at their upper ends to the hubs x at the inner sides of the extreme pulleys k , and carrying at their lower ends a rotary shaft, n^2 , upon which 80 are fastened pulleys k' , of smaller diameter than the pulleys k , and arranged like the latter.

15 It will thus be seen that the brackets D D' and arms D² and D³ are rigid in their vertical positions, though, on loosening or "unkeying" the collars or hubs x in their bearings in the ends of the brackets, the arms D² and D³ may be moved pivotally.

- 20 A wide endless belt or apron, E, Figs. 3 and 4, of canvas or other suitable material, surrounds the pulleys k and k' , and is taut in its position, whereby sufficient friction is produced by the pulleys k against the inner surface of the belt or apron to rotate it and the 85 shaft n^2 and pulleys upon the latter by the rotation of the shaft n' .

25 F denotes buckets or scoops, preferably of flaring form, and also preferably, but not necessarily, concave on opposite sides, as shown. 40 The scoops are of the full width, or substantially so, of the apron E, and are hinged to the latter to extend transversely across it at their tapering ends or bases at intervals of about twice the width of the transverse diameters of the scoops, in order that they may be 45 reversed when it is desired to reverse the motion of the turning apparatus, pivotal buttons or clamps y being provided on the apron at suitable points to engage with the scoops 50 to hold them in either of their two positions. Any required number of scoops may be employed within the capacity of the belt E to accommodate them, and a single one may be employed, if desired.

- 55 The operation of my improved device is as follows: When it is time to stir or "turn" the malt in a vat or any number of the vats A, the belts of the driving-shafts A' are applied to the driving-pulley C of as many of 60 the turning apparatuses as it is desired to move, which by turning the pulley C of each drives it slowly in the desired direction and causes the endless apron E to travel, whereby the scoops F, one after the other in quick 65 succession, take up the malt in the vat on the forward side of the apron and discharge it on the rear side thereof, thereby thoroughly

turning it. When the apparatus reaches the end of the vat opposite that from which it started, it is stopped and its motion reversed, after a desired interval, by suitable arrangement of the driving-belts after turning the buckets F to cause them to scoop the grain and discharge it in a direction respectively the opposite of that hereinbefore described. 75

My improved apparatus may also be made to serve the purpose of a leveler of the grain in a vat after it has been disturbed and rendered irregular on its surface by the turning 80 operation. This I accomplish by raising the elevator portion (afforded by the apron and buckets on the pulleys k and k') by swinging it on the shaft n' , after first loosening the hubs x , to bring the lowest bucket into contact with the surface of the grain, in which position it may be sustained and secured by fastening it with a cable or the like to the frame, and the chain l^2 is disconnected from the sprocket-wheel l' to prevent the traveling 85 motion of the device from affecting the elevator and utilizing such traveling motion only to scrape and thereby level the surface of the grain by means of the bucket in contact with it. If desired, the apparatus may 90 also be used to "rake" the grain automatically from the rear end of a vat to the forward end, at which it is discharged therefrom through a hopper, v . To accomplish this, the elevator may be raised on its pivot to cause a scoop to 95 enter the grain to a desired depth and carry a portion of the surface grain to the outlet, when it may be returned by hand to the rear end and the elevator lowered on its pivot and secured to lower the scraping or raking scoop 100 sufficiently far to scrape the grain to a desired depth below the previously-removed surface, these operations being repeated until the entire contents of the vat have been brought forward to the discharging-point. If 105 desired, brooms or brushes F' may be removably attached to the edges of the scoops 110 F, to sweep the remnants of grain from the floor of the vat, by turning the elevator, as in the malt-turning operation. 115

While my improved apparatus is intended for use especially in the connection described, I do not of course limit myself to such particular connection, as it may obviously be used with any germinating-chamber.

What I claim as new, and desire to secure by Letters Patent, is—

1. In a malt-turning apparatus, the combination of a frame, B, movable on its support, and an elevator having an endless belt, E, carrying a bucket, F, and supported from the frame and driven by its movement and pivotally adjustable on its support, substantially as described. 125

2. In a malt-turning apparatus, the combination of a frame, B, movable on its support, and an elevator comprising an endless belt, E, supported on the frame and connected therewith to be driven by its movement, a 130

bucket, F, hinged to the belt, and thereby reversible in position, and clamps y on the belt for rigidly holding the bucket in its adjusted positions, substantially as described.

5 3. A malt-turning apparatus comprising, in combination, a frame, B, shafts q and q', carrying wheels upon which the frame is supported and movable, a rotary shaft, n', supported from the frame and actuated from the frame-moving mechanism and carrying pulleys k, a shaft, n², connected with the shaft n' and pivotally adjustable thereon and carrying pulleys k', an endless belt, E, surrounding the pulleys k and k', and a bucket, F, secured upon the belt, substantially as described.

10 4. A malt-turning apparatus comprising, in combination, a frame, B, shafts q and q', carrying wheels upon which the frame is supported and movable, brackets D and D', extending from the frame, a shaft, n', and means for rotating the same, and supported in the brackets and actuated from the frame-moving mechanism, and carrying pulleys k, a shaft, n², connected with the shaft n' and pivotally

adjustable thereon and carrying pulleys k', an 25 endless belt, E, surrounding the pulleys k and k', and a bucket, F, secured upon the belt, substantially as described.

5 5. A malt-turning apparatus comprising, in combination, a frame, B, shafts q and q', carrying wheels upon which the frame is supported and movable, a shaft, n, and means for rotating the same, driven from a shaft, q or q', brackets D and D', rigidly secured to the frame, a shaft, n', supported in the brackets 30 and driven from the shaft n and carrying pulleys k, arms D² and D³, pivotally supported from the brackets and normally secured against pivotal movement and carrying a rotary shaft, n², having pulleys k', and an endless belt, E, surrounding the pulleys k and k' and provided with reversible buckets F, hinged to the endless belt, and clamps y, substantially as described.

WILLIAM GRIESSEER.
